UNITED STATES PATENT OFFICE

DORSEY F. ASBURY, OF BROOMES ISLAND, MARYLAND

RADIO APPARATUS

Application filed February 7, 1927. Serial No. 166,516.

My invention relates to radio apparatus and has particular reference to improvements in operating means for the movable parts of tuning units, such for example, as variable plate condensers, my object being to provide an operating means of simple, inexpensive construction whereby the movable parts of a plurality of tuning units may be connected together for convenient collective and individual operation for the various purposes set forth in my prior applications serially numbered 683,756; 689,338; 10,293; 72,514; 80,833; 89,448; 91,197; 95,138; 98,558; 108,074, and 155,016 and in my Patents 1,598,415; 1,598,441; 1,605,804 and 1,605,805.

More particularly it is my purpose to provide a single operator for the movable parts of a plurality of tuning units so constructed and arranged with respect to the units that the movable parts of the units may be moved thereby both collectively and individually and yet the operator can have only a single definite position when all of the units are accurately in tune with any given wave length, the result being that it is possible according to my present invention so to log the operator when it is applied for example to a plural tuning unit radio receiving set that a person desiring to tune the set with a particular broadcasting station the wave length of which is known may do so immediately simply by setting the operator in the one definite known position in which it is possible to set it to have all units tune accurately with that wave length, the necessity of first securing rough and then fine adjustments of the different units as has heretofore been required to secure the same result thus being entirely eliminated without the necessity of employing means as proposed in certain of my prior applications and patents to move the movable parts of the units variable amounts with respect to one another as they are moved collectively.

In order to accomplish the foregoing purpose I provide an operator having different forms of movement to move the movable parts of the tuning units to which it is applied, so that the said movable parts may be moved either individually or collectively, and

in connection with such an operator it is my further purpose to provide means for indicating when it is in position to cause all units to tune with any particular wave length thereby to facilitate setting of the operator in its different definite positions.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a front elevation, partly in section, of a plural tuning unit radio apparatus showing a preferred form of my improved operating means associated with the movable parts of said units;

Figure 2, a horizontal section on the line 2—2 of Fig. 1;

Figure 3, a central vertical section through the apparatus shown in Figures 1 and 2;

Figure 4, a detail perspective of an element of my improved apparatus;

Figure 5, a fragmentary sectional view through a plural tuning unit radio apparatus showing a modified form of my improved operating means associated with the movable parts of the tuning units thereof;

Figure 6, a view similar to Figure 5 showing a position of the operator disclosed in Fig. 5 for operating the movable part of one of the tuning units individually;

Figure 7, a horizontal section through a plural tuning unit radio apparatus disclosing a further modified form of my improved operating means for the movable parts of the tuning units thereof;

Figure 8, a vertical section on the line 8—8 of Figure 7;

Figure 9, a front elevation of the structure shown in Figures 7 and 8;

Figure 10, a horizontal section through a plural tuning unit radio apparatus disclosing still another modified form of my improved operating means for the movable parts of the tuning units thereof;

Figure 11, a front elevation, partly in section, of the structure illustrated in Figure 10.

Figure 12, a view similar to Fig. 1 disclosing still another modified form of my invention; and

Figure 13, a vertical section through the structure shown in Fig. 12.

Referring to the drawings in detail, it will be observed that the tuning units the movable parts of which are intended to be operated by my improved operating mechanisms are indicated in the disclosure of each form of my invention as variable plate condensers, each including, as usual, a set of stator plates *a* and a set of rotor plates *b*, the latter constituting the movable parts of said units. It is to be understood, however, that the tuning units are illustrated herein as variable plate condensers merely for convenience, since they may be of any other form, such, for example, as coils, the only essential being that each of them include a part movable to effect tuning thereof with different wave lengths in order that my improved mechanisms may be adapted to their operation.

In a preferred embodiment of my invention as disclosed in Figures 1 to 4, the tuning units, two in number, are mounted in any suitable manner upon any suitable support such as a base board 10 in side by side spaced relation and with the axes of their rotor shafts 12 disposed in parallelism. On an end of the rotor shaft of one unit is fixed a spur gear 14 and on the corresponding end of the rotor shaft of the other unit is fixed a spur gear 16. A shaft 18, located between the tuning units and disposed normally in parallelism with the rotor shafts of said units, is pivoted at one end as at 20 to a bracket 22 secured to the base board 10 for swinging movement in a plane at right angles to a plane including the axes of the rotor shafts of the tuning units, and upon the other end portion of said shaft is rotatably mounted a knob or dial 24 which extends through an opening 26 in a panel board 28 to the exterior of the apparatus where it may be grasped for manipulation. Opening 26 is elongated in the direction of pivotal movement of shaft 18 and one side wall 30 thereof is disposed substantially in alignment with the pitch line of the teeth of gear 14 while the other side wall 32 thereof is disposed substantially in alignment with the pitch line of the teeth of gear 16, this for a purpose which will presently appear. A spur pinion 34 is located between and in mesh with the spur gears 14, 16, and is connected to the knob or dial 24 by any suitable yieldable means such as the circularly corrugated web 36 illustrated in Fig. 1 whereby the knob or dial may be moved laterally a slight amount sufficient to bring a circular portion 38 thereof against either of the walls 30 or 32 without affecting the toothed engagement between said spur pinion and

said spur gears, said web serving at the same time to assure rotation of the spur pinion 34 at all times with the knob or dial 24. Between the knob or dial 24 and a flange 40 on shaft 18 is arranged a crimped washer 42 affording a friction device serving to resist rotation of said knob or dial with respect to shaft 18, so that said knob or dial will remain in any rotatable adjusted position in which it is placed. Another friction device indicated generally at 44 serves to resist pivotal movement of shaft 18, so that it will remain in any pivotally adjusted position in which it is placed said device 44 being secured to a fixed support such as base board 10 and including, as shown in Figure 4, a pair of yieldable arms 46, 46 between which the shaft is slidable, the normal distance between said arms being less than the diameter of the shaft whereby the necessary friction is afforded by said arms to resist pivotal movements of the shaft.

Friction device 44 serves to maintain shaft 18 normally midway between the rotor shafts of the tuning units so that the cylindrical surface 38 of the knob or dial 24 is spaced slightly from both of the side walls 30, 32 of the opening 26, said shaft being capable of slight flexure, however, so that by pressing laterally upon said knob or dial its aforesaid cylindrical surface may be moved into engagement with either of the walls 30 or 32 of said opening 26. As a result of this arrangement it is apparent that knob or dial 24 has two different forms of movement by which the spur gears 14, 16 and consequently the movable parts of the tuning units may be moved collectively, one of said forms of movement being rotation when the cylindrical surface 38 is spaced from both of the walls 30, 32 and the other being a body movement in a direction at right angles to a plane including the axes of the rotor shafts of the units, the latter form of movement being permitted by pivoting the shaft 18 as at 20 and by elongating the opening 26 in the direction of pivotal movement of said shaft as aforesaid.

The tuning units are duplicates of one another, but are arranged in reversed relation, so that rotation of pinion 34 in one direction will serve to increase the amount of overlap between the rotor and stator plates of both units and rotation of said pinion in an opposite direction will serve to decrease the amount of overlap between the rotor and stator plates of both units. Consequently it follows that by bodily shifting the knob or dial 24 in either of its two permissible directions, the amount of overlap between the rotor and stator plates of one unit will be increased and the amount of overlap between the rotor and stator plates of the other unit will be decreased. In other words, it may be said that rotation of the knob or dial 24 will

5 impart movements to the movable parts of the units to secure like tuning results from each of them, while movement of said knob or dial bodily will impart movements to the movable parts of the units to secure unlike tuning results therefrom. On the other hand, by pressing the knob or dial slightly laterally in one direction, its cylindrical surface 38 will be caused to contact with the wall 30, so

10 that by then rotating said knob or dial while maintaining its cylindrical surface 38 in contact with said wall a rolling action of the knob against said wall will occur and spur pinion 34 as a result will, in effect, pivot about spur gear 14 and as a consequence rotate spur gear 16 individually, spur gear 14 remaining stationary due to the wall 30 being alined with the pitch line of the teeth of said gear, so that as the knob rolls against said wall, pinion 34

15 also rolls against gear 14. By pressing the knob laterally in an opposite direction and simultaneously imparting a rotary movement thereto, cylindrical surface 38 will roll on wall 32 and as a consequence pinion 34 will 20 pivot about gear 16 with resultant individual rotation of gear 14.

25

It will be noted that when the knob or dial is rolled against either wall 30 or 32 the spur gear which is alined with the wall against which the knob or dial is rolled will be held 30 against rotation by the pinion 34 due to the rolling action of the latter against the gear.

35 As a result of the arrangement of parts having the mode of operation described in the foregoing the manipulation necessary to tune both of the tuning units accurately with any particular wave length is apparent: First, the knob or dial 24 is rotated to move the movable parts of the units collectively until each is approximately in tune with the 40 wave length desired. When this has been done the operator then may be shifted bodily to increase the capacity of one unit and decrease the capacity of the other if this is necessary to bring each unit accurately in tune with the desired wave length, or, if one unit has 45 been tuned accurately with the desired wave length as a result of the collective operation and only the other unit requires further adjustment to bring it into accurate tune with the same wave length, operation of the individual unit requiring adjustment may be effected by rolling the knob against one or the other of the walls 30 or 32.

50 Since the pinion 34 is located between and remains at all times in mesh with the gears 14, 16 and since the latter are rotatable in opposite directions to accomplish the same tuning effects in each unit, it follows that the 55 knob or dial 24 can have only a single definite position when each unit is accurately tuned with any particular wave length, and this being true it follows that the various definite positions assumed by the knob when 60 the apparatus is in accurate tune with dif-

ferent wave lengths, respectively, may be logged or indicated, so that whenever it is desired to tune the apparatus with a particular wave length all that is necessary is to move the operator to the single definite position it can occupy when the units are in 70 tune with that wave length. In other words, since the knob 24 must have a definite position of rotation as well as a definite position bodily when both units are in tune with a particular wave length, it is manifest that once 75 the correct rotated and bodily moved positions of the knob are known for correct tuning of the units with a particular wave length any suitable means may be employed for indicating these positions, so that if subsequently it is desired to tune the apparatus with that particular wave length, such tuning 80 may be accomplished instantly simply by positioning the knob in a definite position through the instrumentality of said indicating means. For example, an index such as an arrow 48 may be provided on the panel 28 and graduations 50 may be provided on the knob or dial 24, so that when a particular one 85 of the graduations on the knob or dial is registered with the arrow on the panel the person operating the apparatus will know that the correct rotated position of the knob or dial has been reached to assure correct tuning of the units with a particular 90 wave length. If the knob or dial could partake of material movement bodily a second index such as an arrow could be provided on the panel for registry with another of the 95 graduations on the knob or dial to indicate the correct position of the knob or dial bodily 100 for correct tuning of the units with that wave length, but since bodily movement of the knob or dial rotates the movable parts of the 105 units oppositely with respect to one another as regards tuning effects and since such movement of the knob or dial must therefore of necessity be relatively slight as it serves merely to produce a synchronized relation of the 110 units for different wave lengths, it is desirable to provide means which will indicate in a magnified manner movements of the knob or dial bodily to facilitate accurate bodily positionment of the same. To this end I 115 mount on the panel 28 a short shaft 52 and fix to one end thereof exteriorly of the panel an arm 54 terminating in a pointer 56 adapted for cooperation with a series of 120 graduations 58. Shaft 52 further has fixed thereto a short arm 60 to which is pivoted one end of an arm 62 the other end of which is connected with the shaft 18. Consequently any shifting movement of the knob or dial bodily will act through this mechanism to 125 swing the arm 54 and its movement will be proportionately greater than the movement of the knob due to the difference in length of said arm with respect to arm 60. Since movement of the knob or dial bodily will 130

swing the arm 54 it follows that swinging movement of said arm will move the knob or dial bodily and since it is desirable to utilize the arm 54 to move the knob rather than to move the knob directly, although either of these modes of operation may be practiced, the arm 54 preferably is provided with a small knob 64 as a means of conveniently swinging the same. Thus, once the correct rotated and bodily moved position of the knob 24 is known to assure accurate tuning of both units with any particular wave length the only operation required to tune the apparatus at any time with that wave is to grasp the knob 64 and move it to register its pointer 56 with a particular one of the graduations 58 and rotate the knob or dial 24 until a particular one of the graduations thereon is registered with the index 48.

In further explanation of the fact that the knob or dial 24 can have only a single definite position when both tuning units are tuned accurately with any particular wave length it may be pointed out that if the correct rotated and bodily moved positions of the knob or dial were known for accurate tuning of the units with every wave length within the capacity of the apparatus no necessity for the provision of means for individually operating the units would exist, as such means never is used in tuning the apparatus with any particular wave length once the correct rotated and bodily moved positions of the knob or dial to secure accurate tuning of the units with that wave length are known. Since, however, it is necessary to adjust the units individually when determining initially the correct rotated and bodily moved positions of the knob or dial to secure accurate tuning of both units with any particular wave length the utility of means for individually adjusting the units is apparent, even though such means is never used for tuning the units with any particular wave length once the one definite position of the knob or dial to secure accurate tuning of the units with that wave length has been determined.

In the embodiment of my invention illustrated in Figures 5 and 6 the tuning units, although not shown, are assumed to be duplicates of and to be arranged in the same manner as the tuning units shown in Figures 1 and 2, and to carry, respectively, on their rotor shafts, spur gears 14', 16'. Located between and in mesh with said gears is a spur pinion 34' carried by an operating knob or dial 24' which knob or dial extends through an opening 26' in a panel 28' to the exterior of the apparatus where it may be grasped for manipulation. Said knob or dial is pivoted for universal movement upon a spherical enlargement 66 at one end of a shaft 18' which shaft is pivoted at its other end to a bracket (not shown) the same as shaft 18 of the embodiment of my invention shown in Figures

1 to 3, so that it is non-rotatable but can swing in a direction at right angles to a plane including the axes of the rotor shafts of the tuning units. A friction device 44' similar to the friction device 44 of Figures 1 to 3 serves to retain shaft 18' in any pivotally adjusted position in which it is placed, and to hold the knob or dial 24' normally in axial alignment with said shaft, a straight resilient rod 68 of small diameter is engaged neatly at one end in an opening in the enlargement 66 which is rigid with said shaft and at its other end is engaged neatly in an opening in a plug member 70 which is rigid with said knob or dial. This rod while thus serving normally to maintain the axis of the knob or dial 24' in alignment with the axis of shaft 18' nevertheless permits pivotal movement of the knob or dial about the enlargement 66 as is apparent. Rigid with the knob or dial is an annular flange 72 having a convex outer surface disposed in alignment with the pitch line of the teeth of pinion 34'. A pair of fixed supports 74, 76 are located, respectively, adjacent the points of contact of pinion 34' with the gears 14', 16' and these supports normally are in slight spaced relation with respect to the outer convex surface of flange 72. It will be apparent from this arrangement that exertion of the knob 24' to move the spur gears 14', 16' is exactly the same as described in connection with knob 24 of Figures 1 to 4, except that instead of a cylindrical surface of the knob being rollable against one side or the other of the opening in the panel through which the knob extends to secure individual operation of the units, this result is attained in the modified form of my invention first by tilting the knob as shown in Fig. 6 to bring the outer face of flange 72 into contact with one or the other of the supports 74, 76 and then rotating the knob so that it will react from the support with which it is in contact by pivoting thereon to move the gear remote from said support individually. In all other essential respects this modified form of my invention has the same mode of operation and accomplishes the same results as the form shown in Figures 1 to 4.

In Figures 7 to 9 of the drawings I have illustrated another embodiment of my invention which differs from the embodiments thereof shown in Figures 1 to 6 mainly in that bevel gears instead of spur gears constitute the driving connection between the operating knob and the rotors of the tuning units. In producing this latter form of my invention the tuning units are mounted in any desired manner in relative spaced relation upon a suitable support such as the base board 10 of the apparatus with their rotor shafts in alignment with one another, adjacent ends of said rotor shafts being equipped with bevel gears 14", 16", respectively. A bracket 22", also secured to the base board, carries a pivot

pin 20^a, the axis of which is in alignment with the axes of the rotor shafts of the tuning units, and mounted for swinging movement about said pivot pin is an arm 18^a having rotatably mounted thereon a knob 24^a carrying a bevel pinion 34^a in mesh with the bevel gears 14^a, 16^a. A cupped washer 42^a mounted on arm 18^a and engaging knob 24^a serves frictionally to resist rotation of the latter, while another friction device 44^a, similar to that shown in Figure 4 of the drawings, engages arm 18^a and serves frictionally to retain said arm in any pivoted position in which it is placed. An annular flange 38^a on the knob 24^a has a conical surface for cooperation with either of a pair of fixed supports 30^a, 32^a which supports may conveniently be carried by the frame portions of the respective tunings units. Support 30^a has a surface disposed in alignment with the pitch line of the teeth of gear 14^a while support 16^a has a surface disposed in alignment with the pitch line of the teeth of gear 16^a. As a result of this arrangement it is apparent that by pressing 25 the knob 24^a laterally its flange 38^a may be caused to contact with one or the other of the supports 30^a or 32^a, so that by then rotating the knob it will roll against the support with which flange 38^a is in contact and in effect 30 pivot about its point of contact with said support to rotate the gear 14^a or 16^a, as the case may be, which is remote from said support, it being understood that the amount of tilting movement of said knob necessary to bring 35 its flange 38^a into contact with either support 30^a or 32^a is so slight that the normal play between the teeth of bevel pinion 34^a and bevel gears 14^a, 16^a will permit such movement. Knob 24^a, as is obvious, is rotatable about its 40 own axis as well as swingable about pivot pin 20^a to move the gears 14^a, 16^a collectively and for the same reasons set forth in connection with the disclosure of Figures 1 to 4 of the drawings said knob can have only a single 45 definite position when the units are in accurate tune with any particular wave length. Furthermore said knob is graduated as at 50^a for cooperation with an index 48^a on the panel to indicate definite rotated positions thereof, while a pivoted arm 54^a is connected with arm 18^a in the same manner that arm 54 of Figures 1 to 3 is connected with shaft 18 of said figures for cooperation with graduations 58^a to indicate definite bodily moved 55 positions of said knob. It will be noted in respect to knob 24^a that if the indicating arm 54^a is disconnected therefrom, said knob may have unlimited swinging movement bodily about pivot 20^a for rotating the gears 14^a, 60 16^a collectively, in which event the supports 30^a, 32^a will extend for a considerable distance concentric to the axes of the gears 14^a, 16^a, so that in any bodily moved position of said knob it may be pressed laterally against 65 said supports to move said gears individually.

In Figures 10 and 11 I have illustrated a further modification to show that it is possible to retain the advantages inherent to the forms of my invention previously disclosed in a structure including an operator common 70 to a pair of tuning units having only rotary movement to move the movable part of one of the units and which is rotatable, swingable bodily and rollable to move the movable part of the other unit, while at the same time having only a single definite position when both units are tuned accurately with any particular wave length. According to this form of my invention the tuning units are mounted one behind the other with the axes of their 75 rotor shafts disaligned, but extending in parallel directions equal distances radially from a spherical pivot member 20^b and spaced circumferentially with respect to said pivot member 90° apart. A spur gear 14^b is 80 fixed to the rotor shaft of one unit and a spur gear 16^b is fixed to the rotor shaft of the other unit. The spherical pivot member is carried by a bracket 22^b secured to any suitable fixed support to which the tuning units are secured 85 and is located in the plane of the gear 14^b of one of the units as shown. Mounted on said pivot member for universal movement with respect thereto is a spur pinion 78 which meshes with spur gear 14^b. Fixed to said 90 pinion is a shaft 18^b which extends across the other tuning unit and has fixed thereto an operating knob 24^b carrying a spur pinion 34^b meshing with gear 16^b. Knob 24^b extends through an opening 28^b in a panel 28^b 100 and includes a cylindrical surface 38^b adapted for cooperation with a wall 32^b of said opening which, as shown in Fig. 11, is in alignment with the pitch line of the teeth of gear 16^b. A short shaft 52^b is mounted in panel 28^b and carries at one end an indicator 105 arm 54^b and at its other end a short arm 60^b to which is pivoted on end of an arm 62^b which, at its other end, is pivoted to shaft 18^b. A friction device 44^b similar to that shown 110 in Fig. 4 engages arm 62^b. As a result of this arrangement it is apparent that with the cylindrical surface 38^b spaced from wall 32^b rotation of the knob 24^b will rotate the gears 14^b, 16^b collectively, while gear 16^b may be 115 rotated individually simply by moving said knob laterally without rotating same. On the other hand gear 14^b is rotatable individually by pressing the knob to bring its cylindrical surface 38^b into contact with wall 120 32^b and then rotating the knob, this resulting in rolling movement of the pinion 34^b with respect to gear 16^b without moving the latter and in rotation of pinion 78 to rotate gear 14^b. Knob 24^b is graduated as at 50^b for cooperation 125 with an index 48^b to indicate the one definite rotated position it can occupy when both units are accurately tuned with any particular wave length, while arm 54^b indicates the one definite bodily moved position said 130

knob can occupy when the units are accurately in tune with any particular wave length.

In Figures 12 and 13 of the drawings I have illustrated a further modification of my invention differing from the preceding embodiments thereof essentially in that means is provided whereby the operator, instead of being rollable against a permanent fixed support or supports for moving the movable parts of the tuning units individually, is rollable against a movable part of one unit to move the movable part of the other unit individually, the movable part of the first unit being held against movement during adjustment of the movable part of the second unit whereby it constitutes in effect a fixed support from which the operator reacts to move the movable part of the second unit. In this embodiment of my invention the tuning units are mounted in the same relation as shown in Figure 1 of the drawings, that is, abreast and spaced with respect to one another and with the axes of their rotor shafts disposed in parallelism.

On corresponding ends of said rotor shafts are fixed, respectively, spur gears 14°, 16° and meshing with said spur gears is a spur pinion 34° carried by a knob 24° which is rotatably mounted on a shaft 80 and extends through an opening 26° in a panel 28° to the exterior of the apparatus where it may be grasped for manipulation. An arm 18° is pivoted at one end as at 20° to a bracket 22° for swinging movement in a direction at right angles to a plane including the axes of the rotor shafts of the tuning units. The shaft 80 is pivoted at an intermediate point in its length, as at 82, to the free end of arm 18° for swinging movement in a direction at right angles to the direction of swinging movement of said arm, and carried by the end of said shaft opposite to the end thereof on which knob 24° is mounted is a small roller 84. The spur gears 14°, 16° are provided with lateral flanges 86, 88, respectively, with which brake levers 90, 92 are adapted for co-operation respectively, said brake levers being intermediately pivoted to suitable fixed supports and each having one end disposed in proximity to the inner face of its related flange and its other end disposed in proximity to roller 84. As a result of this arrangement it is manifest that knob 24° is rotatable on shaft 80 as well as bodily swingable about the pivot 20° to rotate the spur gears 14°, 16° collectively. It is manifest also that by swinging said knob in one direction about pivot 82, roller 84 will engage one of the levers 90 or 92 and swing same on its pivot into braking engagement with its related flange 86 or 88 as the case may be, while by swinging said knob about its pivot 82 in an opposite direction roller 84 will be caused to engage the other of said levers and swing same on its pivot into braking engagement with its related

flange. Thus, for example, if knob 24° is swung to the right as shown in Fig. 12 roller 84 will be moved to the left into engagement with one end of lever 90 and swing same on its pivot until its other end is forced into frictional braking engagement with the flange 86 of gear 14°. If now knob 24° is rotated, spur gear 34° obviously must roll on spur gear 14° since the latter is held against rotation and by so rolling on spur gear 14° the other spur gear 16° will be rotated individually by said spur pinion as also is obvious. In exactly the same manner spur gear 14° may be rotated individually by first swinging knob 24° to the left as shown in Fig. 12 and then rotating said knob. An indicator arm 54° is connected with arm 18° in the same manner as shown in Fig. 1 to indicate the different definite bodily moved positions of the knob 24° when the units are in accurate tune with particular wave lengths, and graduations are provided on said knob for cooperation with an index on the panel to indicate the different definite rotated positions of said knob when the units are accurately in tune with particular wave lengths, it being understood that for the same reasons set forth in connection with the structure of Fig. 1, knob 24° can have only a single definite position when both units are in tune with any particular wave length.

From the foregoing description considered in connection with the accompanying drawings it is believed that the construction, operation and advantages of my present invention will be fully understood. I desire to point out, however, that while I have disclosed herein certain specific embodiments of my invention various changes and desirable additions may be made in and to each of them within the spirit and scope of my invention as defined in the appended claims.

I claim:

1. In radio apparatus, a pair of tuning units a part of each of which is movable, an operator having continuous driving connection with the movable part of each unit, means whereby said operator is movable to move the movable parts of said units collectively and individually, and means cooperating with said operator to prevent movement of one unit while the other unit is being moved individually by the operator.

2. In radio apparatus, an adjustable tuning unit, a rotatable and bodily movable actuator constantly in driving connection with said unit, means operable by either of said movements independently of the other to adjust said unit, and a fixed support against which said actuator is adapted to be rolled to adjust said unit.

3. In radio apparatus, a plurality of adjustable tuning units, a rotatable and bodily movable actuator constantly in driving connection with said units, means operable by

- either of said movements independently of the other to adjust said units collectively, and effective by a combination of said movements to adjust one of said units individually, and
- 5 a fixed support against which said actuator is adapted to be rolled to produce a combined rotary and body movement thereof.
4. In radio apparatus, a plurality of adjustable tuning units, a rotatable and bodily
- 10 movable actuator constantly in driving connection with said units means operable by either of said movements independently of the other to adjust said units collectively, and effective by a combination of said move-
- 15 ments to adjust each of said units individually, and a fixed support having separate surfaces against one of which said actuator is adapted to be rolled to produce a combined rotary and body movement thereof effective
- 20 to adjust one of said units individually and against another of which said actuator is adapted to be rolled to produce a combined rotary and body movement thereof effective to adjust another of said units individually.
- 25 5. In radio apparatus, a plurality of adjustable tuning units, an actuator having different forms of movement, connections between said actuator and units responsive to one form of movement of the actuator, to
- 30 adjust said units collectively in the same tuning status direction and to another form of movement of the actuator to adjust said units collectively in opposite tuning status directions, and means to indicate the correct
- 35 amount of each of said forms of movements with respect to the other to bring each of said units into accurate tune with any given wave length.
6. In radio apparatus, a plurality of ro-
- 40 tatably adjustable tuning units, a gear wheel on each unit, a pinion located between and in mesh with the gear wheels on said units, an actuator for said pinion, said pinion being mounted for rotation and for shifting move-
- 45 ment bodily and being effective by either of said movements independently of the other to adjust said units collectively and by a combination of said movements being effec-
- 50 tive to adjust said units individually, and a fixed support having surfaces against which said actuator is rollable to produce combined rotary and bodily shifting movements of said pinion effective to adjust said units individ-
- 55 ually.
- 55 In testimony whereof I hereunto affix my signature.

DORSEY F. ASBURY.
